CLAIM

The ornamental design for a *shopping cart*, as shown and described.

DESCRIPTION

FIG. 1 is a rear perspective view of my new design [of] for a *shopping cart* showing my claimed design;
FIG. 2 is a side elevation view of the right and left sides, which are mirror images, of FIG. 1[.];
FIG. 3 is a front side elevation view of FIG. 1[.];
FIG. 4 is a [back] rear side elevation view of FIG. 1[.];
FIG. 5 is a top plan view of FIG. 1; and,
FIG. 6 is a bottom plan view of FIG. 1.
The broken [line showing of wheels and bumpers is included for the purpose of illustrating portions of the article and forms] lines shown in the drawings illustrate portions of the shopping cart that form no part of the claimed design.

1 Claim, 5 Drawing Sheets

Matter enclosed in heavy brackets [ ] appears in the original patent but forms no part of this reissue; matter printed in italics indicates the additions made by reissue.
